UNITED STATES PATENT OFFICE.

WILLIAM L. PERRY, OF SCRANTON, PENNSYLVANIA.

CARBURETER.

No. 926,696.

Specification of Letters Patent. Patented June 29, 1909.

Application filed December 27, 1907, Serial No. 408,308.

To all whom it may concern:

Be it known that I, WILLIAM L. PERRY, a citizen of the United States, residing at Scranton, in the county of Lackawanna and State of Pennsylvania, have invented certain new and useful Improvements in Carbureters; and I do hereby declare the following to be a full, clear, and exact description of the invention, such as will enable others skilled in the art to which it appertains to make and use the same.

This invention relates to improvements in carbureters, and particularly to improved carbureters adapted for use with vapor engines or internal combustion engines, as well as in other places where it is desired to employ gasoline, kerosene, or other liquid hydrocarbon as fuel.

The invention comprises the provision of means for correctly mixing the hydrocarbon with air, and for supplying varying quantities of either air or hydrocarbon oil under varying demands, for the mixture.

The object in view is the provision of means for maintaining a proper mixture of hydrocarbon and air regardless of the amount of mixture demanded.

Another object in view is the automatically varying the entrance of air and hydrocarbon for always maintaining a proper mixture automatically under varying demands.

A still further object in view is the provision of mechanism that will not require springs and the like for causing an automatic operation of the air regulating means and oil regulating means.

With these and other objects in view the invention comprises certain novel constructions, combinations, and arrangement of parts as will be hereinafter more fully described and claimed.

In the accompanying drawing: Figure 1 is a vertical section through a carbureter embodying the features of the present invention. Fig. 2 is a section through Fig. 1, on line 2—2. Fig. 3 is a top plan view of a discharge nozzle or atomizer being shown in connection therewith. Fig. 4 is a vertical section through the atomizer with a slightly modified form of regulating means secured thereto.

It is well known that to obtain the best results and the least expenditure of oil in engines and the like, the mixture of oil and air must be of the proper proportion, neither

too much nor too little. In addition to providing a structure for accomplishing this desirable result the present invention is aimed to provide means whereby the proper mixture of oil and air may be obtained with varying demands upon the carbureter, so that without any manual adjustment a large quantity of oil and air may be drawn from the carbureter, or a comparatively small amount of air may be drawn from the carbureter, and in either case be properly mixed for burning as fuel in any desired way, as, for instance, an internal combustible engine.

Referring more particularly to the drawing, 1 indicates a mixing chamber which has leading therefrom a discharge opening 2. The discharge opening 2 has positioned therein a valve or cut-off 3 operated by a handle 4 for positioning the valve in any desired position for permitting any desired quantity of mixture from mixing chamber 1 to be drawn out for use. Suitable lugs or securing members 4 and 5 are provided for securing the carbureter in position. Surrounding the lower part of opening 2 and immediately above mixing chamber 1 is a chamber or receptacle 6 having mounted therein a balancing piston 7 provided with relieve passes 8. Receptacle 6 is entirely closed so that as piston 7 operates therein and moves from the top toward the bottom, or vice-versa, the air on one side of the piston must pass through relieve passes 8. This will prevent piston 7 which may be termed a perforated retarding piston from any sudden or quick movement and also prevent valve 9 from any sudden or quick movement as the same is rigidly connected with piston 7. Any desired number of connecting rods 10 are secured to piston 7 and in turn have secured thereto arms 11, which are firmly riveted or otherwise secured to valve 9 so that any movement of valve 9 is communicated to piston 7, and also any movement, as by law of gravity, of piston 7 is communicated to valve 9. Passing through valve 9 and loosely fitting therein is a tube or atomizer casing 12 that is provided with arms 13 and 14 which are firmly secured to a tubular extension 15 of mixing chamber 1. By this structure atomizer casing 12 is always held in one position but valve 9 is permitted to reciprocate and is moved according to the amount of mixture required in the carbureter.

reter, the valve remaining against the seat or bottom of mixing chamber 1 when no mixture is required and is raised in proportion to the amount of mixture required. Atomizer 5 casing 12 is also formed with holes or apertures 16 and 17 that are in turn provided with valve members or plugs 18 and 19, the valve members or plugs 18 and 19 being mounted in the tubular extension 15 but 10 adapted to be brought into proximity to holes or apertures 16 and 17, for closing the same and again removed therefrom for permitting air to pass therethrough.

Rigidly secured to valve 9 are a plurality 15 of supports or connecting rods or bars 20 and 21 which have secured to their lower ends a cup shaped regulator 22 which is adapted to move upward and downward with valve 9. The upper part of regulator 22 is open and 20 the lower part closed with the exception of a small opening 23 through which discharge nozzle 24 projects. Discharge nozzle 24, however, does not entirely fill opening 23 so that a certain amount of air may pass there- 25 through over the top of nozzle 24 together with air passing from over the top or cup 23 down to the lower end of atomizer casing 12.

Rigidly secured to valve 9 is a support 25 that has secured thereto a substantially con- 30 ceal shaped deflector or plug 26 that, when in its lower most position, will substantially fill the upper end of atomizer casing 12. This deflector is designed to commingle and also to check the flow of air and liquid through 35 atomizer casing 12 while valve 9 is designed to check and regulate the flow of air into mixing chamber 1. By the entrance of the air in the tube 23 and also from the top of cup shaped member 22 a draft is supplied for 40 drawing oil from discharge nozzle 24 for carrying the same upward into mixing chamber 1. This oil and air is usually too rich in oil to be a proper mixture for proper ignition, and consequently air is permitted to flow 45 into mixing chamber 1 around valve 9 from air chamber 27. The air passing from chamber 27 through or around valve 9 mixes with the oil laden air passing from the end of atomizer casing 12 and from thence passes 50 upward through discharging opening 2, the sucking action from the engine or other device creates a partial vacuum or tendency toward a vacuum in mixing chamber 1, which causes the air to pass through opening 55 23 and also air to pass into mixing chamber 1 around valve 9 and from thence on out, mixing as it goes. By this action the air drawn around valve 9 and the oil drawn from nozzle 24 is in correct proportion for forming 60 a proper mixture for ignition. If for any reason it is found that there is not a sufficient draft through the tube of atomizer casing 12 to suck or draw out of discharge nozzle 24 sufficient oil, plug or valve members 18 and 65 19 are moved toward graduating airways or

apertures 16 and 17 and then the suction from above will draw less air in through these apertures, causing more suction on nozzle, this causing it to deliver additional oil to the mixing chamber.

Surrounding air chamber 27 is an annular chamber 28 designed to receive oil and to have a certain amount maintained therein at all times, preferably such amount as to bring the upper surface of the oil on an approxi- 70 mate line with the upper edge of the discharge nozzle 24. Connecting nozzle 24 with annular chamber 28 is a passage way 29. Passage way 29 is formed with an aperture or opening 30. A valve 31 is positioned in passage way 29 for manually regulating the amount of oil passing from annular chamber 28 to nozzle 24. By this means the oil fed to discharge nozzle 24 may be checked or regulated manually, but ordinarily valve 31 is open 80 fully, for permitting the free flow of oil from chamber 28 to nozzle 24, the automatic operation of valve 9 and the remaining automatic mechanism, regulating the amount of oil used when taken in connection with the amount of suction or draft exerted upon opening 2. Nozzle 24 may be secured in passage way 29 in any convenient manner as being screw threaded therein and has in connection therewith a plug 32 fitted into passage way 29 in line with the nozzle so that the same may be easily cleaned out whenever desired.

Mounted in annular chamber 28 is a float 33 of such a weight as to hold open valve 34 until the oil in annular chamber 28 has reached a level equal to substantially the top of nozzle 24, and then permit the closing of valve 34. A bifurcated member 35 is pivotally mounted at 36 at the bottom of chamber 28 and has the bifurcated arms thereof normally resting against the bottom of the annular float 33, so that when the oil in annular chamber 28 has reached a predetermined level weight 37 will close valve 34. It will also be evident that when the oil in chamber 28 has lowered, float 33 will be lowered, and consequently acting upon member 35 will raise valve 34 for permitting oil to flow from passage way 38 into chamber 28, oil being fed from any desired source to passage way 38. It will be observed that if desired cup shaped regulator 22 may be removed and the amount of air passing through atomizer casing 12 regulated by member 26, 105 though ordinarily regulator 22 is used for giving a double regulation.

In Fig. 4 will be seen a slightly modified form of regulating means for regulating the amount of oil fed to mixing chamber 1. In this figure a cup or receptacle 39 is provided that is designed to snugly fit within the upper end of atomizer casing 12. Receptacle 39 is provided with longitudinal apertures or slots 40 and is also designed to be open at one end 110

as 41 so that air and oil passing into it through atomizer casing 12 will be permitted to pass out through apertures 40 into mixing chamber 1. Receptacle 39 is rigidly secured to supporting member or bracket 42 which acts as a top or cover for the receptacle and also as a support therefor, the support being firmly secured to valve member 9 for simultaneous movement therewith. In addition to the receptacle 39 another auxiliary regulating cup 43 is provided at the lower end of the atomizer casing 12, which acts in a similar manner to cup 22. Regulator 43 is also arranged with elongated slots or apertures 44 in a similar manner to regulator 39, or the slots can be made in atomizer casing 12 so arranged as to be made to close as the sleeve or cup 43 moves upward, in which case the openings 44 are not made in 43. It will be evident that cup 43 can be made to either go inside or outside of atomizer casing 12; both producing practically the same result. In use regulator 39 may be used separately or in conjunction with regulator 44 as may be desired, though ordinarily the use of two regulators is desirable as the regulation is more even.

In operation when it is desired to receive an explosive mixture from passage way 2 a vacuum or partial vacuum is created by the turning over of the engine or by any other desired means, which will consequently suck or draw air through atomizer casing 12, together with a quantity of oil, and in addition will draw air around valve member 9. This air drawn around valve member 9 and the oil laden air drawn through atomizer casing 12 mixes in chamber 1, and from thence passes out passage way 12 to be used as may be desired. In case a large amount of combustible mixture is desired the suction is comparatively great so that a comparatively large amount of oil laden air will be drawn through atomizer casing 12, and a comparatively large amount of air drawn around valve member 9, valve member 9 being raised from its seat in proportion to the strength of the suction. This air and oil for mixing in chamber 1 will pass out through passage way 2. To prevent any sudden or unusually quick action of valve member 9 or the too quickly drawing oil from nozzle 24, a check or damping member, as piston 7, is provided. Any tendency that valve 9 has to rise will be damped by piston 7, but will not be prevented, and also piston 7 will by its weight give a continued tendency to close valve 9, so as not to let an undesirable amount of air in the chamber 1. By this construction and arrangement a proper mixture of oil and air is provided during varying demands on the carburetor, so that when a comparatively small amount of mixture is desired a comparatively small amount will be delivered, and that in proper proportion.

When a larger amount is desired a larger amount will be delivered, and also delivered in the proper proportion, by reason of the relative action of the drawing of oil from nozzle 24 through atomizer casing 12, and the drawing of air around valve 9. Any desired number of binding or connecting bolts 45 may be provided for holding the various chambers and parts together.

What I claim is:

1. In a carburetor, a mixing chamber having an air inlet port, a regulating valve in said chamber controlling said port, an annular air chamber formed with a passage way therethrough which forms an outlet from said mixing chamber, and a perforated retarding piston working in said air chamber and having connection with said valve for dampening the motion thereof.

2. In a carburetor, a mixing chamber having an air inlet port, a tube, a fuel supply nozzle extending into said tube, a regulating valve controlling said inlet port, and means supported from said valve and closing the lower end of said tube, said means being movable with the valve and arranged to control the passage of air into said tube through the lower end thereof.

3. In a carburetor a mixing chamber having an air inlet port, a tube, a supply nozzle extending into the tube, a regulating valve controlling said inlet port, and a tapered member supported from the valve and inclosing the lower end of the said tube, the said member being movable with the valve and being arranged through such movement to control the passage of air into the tube through the lower end thereof.

4. In a carburetor a mixing chamber having an air inlet port, a tube, a supply nozzle extending into the tube, a regulating valve controlling said inlet port, and a hollow tapered member supported from the valve and inclosing the lower end of the tube, the said member being arranged to control the passage of air into the tube through the lower end thereof.

5. In a carburetor a mixing chamber having an air inlet port, a tube, a supply nozzle leading into the tube, a regulating valve controlling said inlet port, and a member supported from the valve and surrounding the lower end of the tube and the upper end of the supply nozzle, the said member being arranged to control the passage of air into the tube through the lower end thereof.

6. In a carburetor a mixing chamber having an air inlet port, a tube, a supply nozzle leading into the tube, a regulating valve controlling said inlet port, and a hollow tapered member supported from the valve and surrounding the lower end of the tube and the upper end of the supply nozzle, the said member being formed with an air passage surrounding the supply nozzle.
